Murray & Borun[57] **CLAIM**

The ornamental design for a broom head, as shown and described.

DESCRIPTION

FIG. 1 is a perspective view of a broom head in accordance with the present invention;

FIG. 2 is a top view;

FIG. 3 is a right-side view, the left-side view being a mirror image thereof;

FIG. 4 is a bottom view;

FIG. 5 is a back view;

FIG. 6 is a front view; and,

FIG. 7 is a top and side perspective view of an alternate embodiment, it being understood that the opposite side is a mirror image of the side shown, the back and front are identical to the back and front shown respectively in FIGS. 5 and 6, and that the bottom except for the length and number of undulations on the sides thereof, is identical to the bottom shown in FIG. 4.

The broken lines in the figures show the placement of bristles, and form no part of the design as claimed.
